(57) **CLAIM**

The ornamental design for a flexible interconnecting member for solar cells, as shown and described.

DESCRIPTION

The present application is also related to U.S. patent application Ser. No. 29/552,355 filed Nov. 4, 2016.

FIG. 1 is a top perspective view of a flexible interconnecting member for solar cells showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof; and,

FIG. 7 is a left side elevation view thereof.

The broken line in the figure drawings is included for the purpose of illustrating environment and forms no part of the claimed design.
